THREAD CUTTING CHASER

Albert F. Breitenstein, New Haven, Conn., assignor to The Geometric Tool Company, New Haven, Conn., a corporation

Application November 9, 1932, Serial No. 641,846

1 Claim. (Cl. 10—103)

This invention relates to an improvement in thread-cutting chasers of the so-called "circular" type, i. e., chasers of substantially-cylindrical form and having thread-cutting teeth formed upon their peripheries. Circular chasers as at present in use fall into two distinct classes, namely, those having truly-annular thread-cutting teeth upon their peripheries, and those having helically-inclined thread-cutting teeth thereon.

My invention relates to the latter class of circular chasers and has for one of its main objects the provision of a circular chaser of the helical-tooth type which, despite repeated grindings of its cutting-face, will have its cutting-teeth located at a substantially-constant distance from its forward face.

A further object of my present invention is to provide a circular chaser of the type referred to in which the throat or chamfer-form will remain substantially the same, despite repeated grindings of the cutting-face.

Other objects will be apparent from the following, taken in conjunction with the accompanying drawing.

With the foregoing and other objects in view as will appear from the following, my invention consists in a thread-cutting chaser of substantially-cylindrical form having helically-inclined thread-cutting teeth, together with certain features and configurations as will be hereinafter more fully set forth.

In the accompanying drawing:

Fig. 1 is a perspective view of one form which 35 a thread-cutting chaser constructed in accordance with my invention may assume;

Fig. 2 is a similar view, but viewing the chaser from a different angle;

Fig. 3 is a view of the chaser in front elevation;

Fig. 4 is a view thereof in side elevation, looking in the direction of the arrow 4 of Fig. 3;

Fig. 5 is a similar view, but looking in the direction of the arrow 5 of Fig. 3;

Fig. 6 is a view of the chaser in edge elevation, looking in the direction of the arrow 6 of Fig. 3;

Fig. 7 is a transverse sectional view, taken on the line 7—7 of Fig. 3; and

Fig. 8 is a transverse sectional view, taken on the line 8—8 of Fig. 3.

The particular chaser herein chosen for the illustration of my invention has a body 10 of substantially-cylindrical exterior form, as shown, and has its periphery formed with a series of 55 grooves 11 which are helically inclined from front

to rear and result in the formation of a similarly-inclined series of thread-cutting teeth 12. The said teeth 12 are interrupted by a notch 13 extending from front to rear of the body with a slight outward slope, and resulting in the formation of a cutting-face 14 which, as will herein-after appear, may be repeatedly ground back as required to keep the chaser in sharpened condition.

The particular chaser illustrated in the accompanying drawing is provided with an axial bore 15 having formed therein an annular series of serrations 16 by means of which it may be properly orientated and anchored to a suitable stud or post, not shown, and forming a feature 60 65 of a die-head or other thread-cutting device.

The rear face 17 of the chaser preferably extends, as shown, at a right angle to the axis of the body 10, while the front face 18 is helically inclined from front to rear at an angle corresponding to the helix angle of the thread-cutting teeth 12 before referred to. It will be appreciated in this connection that the cross-sectional form, as well as the helix angle, of the thread-cutting teeth 12 will vary to meet different re- 70 75

quirements in threading practice, though it is intended that the front to rear inclination of the front face 18, just referred to, shall substantially correspond to the helix angle of the particular thread-cutting teeth formed upon the chaser. 80 The front face 18 of the chaser is also preferably so shaped that despite its helical slope from front to rear, it will extend radially at all points at substantially a right angle to the axis of the chaser, as will clearly appear from Figs. 7 and 8. 90

The forward outer edge or corner of the chaser is chamfered as at 19, which chamfer slopes with respect to the axis of the body and joins the forward face 18 at a point below the root of the thread-cutting teeth 12 to facilitate the starting 95 of a threading operation in accordance with usual practice. In addition to sloping with respect to the axis of the body-member, the chamfer is also ground at a helical angle from front to rear substantially conforming to the helix angle of the 100 thread-cutting teeth 12.

Preferably and as shown, the helix angle of the chamfer 19 slightly exceeds the helix angle of the thread-cutting teeth 12, as will be observed from the extension lines marked upon Fig. 5. This feature will also be apparent from other figures of the drawing. In Figs. 7 and 8, for instance, it will be obvious that the chamfer extends progressively more deeply into the thread-cutting teeth 12 as the distance increases from the cutting-face 110

14. This slight increase in helical angle of the chaser is designed to provide clearance to facilitate the cutting action of the front portion of the chaser.
- 5 By so inclining the front face 18 of the body 10 from front to rear as shown, to substantially conform in helix angle to the helix angle of the thread-cutting teeth 12, any given one of the latter will be found to be located at substantially the 10 same distance from the said front face 18. The feature just referred to will be made clear by reference to Figs. 7 and 8, in which it will be noted, by comparing the distance A marked thereon, that in each instance they correspond.
- 15 As the chaser is subjected to continued use, it will be desirable to repeatedly grind the cutting-face 14 and in time it may be that the said cutting-face will be ground back, for instance, as far as is indicated by the broken lines 14^a in Fig. 3. Despite 20 this grinding back, the character of the cutting-face 14 presented to the work will not materially change, whereas in prior types of circular chasers having helically-inclined thread-cutting teeth, progressive grinding operations 25 will inevitably alter the distance between the front face of the chaser and the cutting-teeth, and thus present a cutting-face of progressively changing character as the cutting-face is ground back for sharpening purposes.
- 30 My improved chaser, if initially designed to cut threads upon a shouldered object up to within a given distance of the shoulder thereon, may have its cutting-face 14 repeatedly ground even to the extent indicated at 14^a in Fig. 3, without materially 35 altering the character of the thread which the chaser will produce upon the work adjacent such a shoulder.

Viewed from another angle, my improved

chaser may be said to have capacity for maintaining the substantial sameness of its chamfer characteristics 19, despite the repeated grinding back of its cutting-face 14.

Thus, instead of constructing a circular chaser which has the same depth from front to rear at any given place adjacent its periphery, my improved chaser may be said to progressively decrease in depth from front to rear in substantial conformity with the helix angle of the thread-cutting teeth thereof.

It will be understood by those skilled in the art that my invention may assume varied physical forms without departing from my inventive concept, and I, therefore, do not limit my invention to the specific embodiment herein chosen for illustration, but only as indicated in the appended claim.

I claim:

A thread-cutting chaser of substantially-cylindrical form and having its periphery helically grooved to form helically-inclined thread-cutting teeth thereon, and having its front face helically inclined from front to rear in the same direction and at substantially the same helix angle as the said helically-inclined thread-cutting teeth; the said chaser having a cutting face extending substantially-parallel to its axis and also having its forward outer edge chamfered along an inclined helical path from front to rear at a helical angle exceeding the helix angle of both the said thread-cutting teeth and the said helically-inclined front face; the rear edge of the said chamfer being of progressively-lessening height above the bottom of the adjacent helical groove.

ALBERT F. BREITENSTEIN.
